[57] CLAIM

The ornamental design for a handle for a faucet or the like, as shown and described.

DESCRIPTION

FIG. 1 is an isometric view of a handle for a faucet or the like showing our new design;

FIG. 2 is a side elevational view thereof;

FIG. 3 is another side elevational view thereof showing the handle unit, rotated forty-five degrees from that shown in FIG. 2;

FIG. 4 is a top plan view thereof;

FIG. 5 is a bottom plan view thereof;

FIG. 6 is an isometric view of handle and cap unit thereof;

FIG. 7 is a side elevational view of FIG. 6;

FIG. 8 is another side elevational view of FIG. 6 showing the handle unit rotated forty-five degrees from that shown in FIG. 7;

FIG. 9 is a top plan view of FIG. 6;

FIG. 10 is a bottom plan view of FIG. 6;

FIG. 11 is an isometric view of the escutcheon thereof; FIG. 12 is a side elevational view of FIG. 11, all sides being the same as the side shown;

FIG. 13 is a top plan view of FIG. 11;

FIG. 14 is a bottom plan view of FIG. 11;

FIG. 15 is an exploded isometric view of FIG. 1;

FIG. 16 is an isometric view of the cap portion thereof;

FIG. 17 is a top plan view of FIG. 16;

FIG. 18 is a bottom plan view of FIG. 16;

FIG. 19 is a side elevational view of FIG. 16, the other side being the same as the side shown;

FIG. 20 is an isometric view of a second embodiment thereof;

FIG. 21 is a side elevational view of FIG. 20;

FIG. 22 is another side elevational view of FIG. 20 showing the handle unit rotated forty-five degrees from that shown in FIG. 21;

FIG. 23 is a top plan view of FIG. 20;

FIG. 24 is a bottom plan view of FIG. 20;

FIG. 25 is an isometric view of the wall escutcheon shown in FIG. 20;

FIG. 26 is a side elevational view of FIG. 25; and,

FIG. 27 is a bottom isometric of FIG. 25.
